FUSEE

Raymond F. Hutt, Fort Madison, Iowa, assignor to
 Anthes Force Oiler Company, Fort Madison,
 Iowa, a corporation of Iowa

Application March 30, 1940, Serial No. 326,851

3 Claims. (Cl. 102—37.52)

The present invention relates to fusees, and more particularly to fusees such as are used by truckers and drivers on the highway. These fusees have for years been used on the railroads and are now required on trucks by the Interstate Commerce Commission. It has been considered that the fusee should be used in conjunction with the flares which, according to many State laws, have to be carried by a trucker and set out when a stop is made upon the highway. The fusee is of advantage for two purposes. It provides an immediate light which the operator may ignite without matches quickly and carry with him when he alights with a minimum danger to himself or to the public. The lighted fusee also functions as an ignition device by means of which the flares which have to be set out are lighted.

The fusee functions from another standpoint as a very useful device in the hands of a trucker. Many loads carried by the truckers, such for example as live stock, are of a changing or shifting nature and require frequent inspections and short stops. Inspection of the tires and other equipment must also be made from time to time. The fusee in the hands of the operator furnishes an excellent light for the inspection purposes and at the same time provides the desirable safety features of warning the public when the operator alights from the cab and of providing means for igniting the flares.

A single fusee for each stop, however, becomes a complicated or unnecessarily expensive device for the trucker. A fusee preferably should be constructed so that it would produce a maximum burning period of around fifteen minutes. This meets the Interstate Commerce Commission requirements on safety and also provides a long burning period in case a stop is longer than had been first anticipated. Most of the stops, however, will be so short that a single fifteen minute fusee would be an expensive luxury for the trucker.

I have provided a novel fusee construction which furnishes a single fusee having the requisite burning time, and which at the same time provides that a maximum of salvage will be obtained in the event the stop or necessity for the fusee is considerably less than the burning time of the whole fusee. For example, the present invention contemplates as a practical embodiment a single fusee capable of burning for a full fifteen minutes, which is so constructed that if, for any reason, the stop is shorter than one-third the normal burning time of the fusee, two-

thirds of the fusee may be salvaged, and this shorter two-thirds may be used for other short stops without adversely affecting its ignition or burning qualities.

5 The features and advantages of the present invention will appear more fully as the description proceeds, reference being had to the accompanying drawings wherein a preferred form of the invention is shown. It is to be understood, 10 however, that the drawings and description are illustrative only and are not to be taken as limiting the invention except insofar as it is limited by the claims.

In the drawings, Fig. 1 is a longitudinal sectional view taken through a complete fusee embodying the present invention;

Fig. 2 is a view in elevation illustrating the manner in which ignition of a fusee takes place;

Fig. 3 is a view partly in elevation and partly 20 in section illustrating how the fusee burns;

Fig. 4 is a sectional view taken on the line 4—4 of Fig. 1;

Fig. 5 is a view partly in elevation and partly 25 in section illustrating the breaking of a partially burned section of the fusee from the remaining unburned sections, and

Fig. 6 is a view partly in elevation and partly 30 in section showing the shorter fusee resulting from Fig. 5 with the cap re-applied.

Referring now in detail to the drawings, the 35 device shown in Fig. 3 is a completed fusee constructed to fulfill the necessary requirements of the Bureau of Explosives and the Interstate Commerce Commission. This fusee includes a base plug 10 which may serve as a mounting for a spike 11 or other suitable supporting means.

The body of the fusee comprises a plurality of sections 12, 13 and 14 of the necessary chemical composition to provide a brilliant flame of the 40 required color. The several sections of the fusee are enclosed in paper tubes 15, 16 and 17 respectively. As shown in Fig. 1, the top tube 17 has its upper end crimped and turned in, as illustrated at 18, so as to seal the top and around 45 the ignition material which is indicated at 19.

Sections 12 and 13 each have embedded in the upper end thereof a body of ignition material, as shown at 20 and 21. If desirable, the tops of the tubes 15 and 16 may be crimped over in the 50 same manner as the top of the tube 17. This, however, is normally not necessary.

The three sections 12, 13 and 14 are housed and connected together by an outer paper tube 22 which also laps over the wooden plug 10 at the 55 base and serves to unite the several parts of the

fusee into a single structure. The thickness of the tubes 15, 16 and 17 and the outer tube 22, are such as to properly control the burning of the fusee without producing enough chimney to materially obscure the flame.

The fusee is provided with a cap 23 which is composed of a wooden scratcher head 24 having the necessary igniting material 25 thereon. A tubular sleeve 26 of paper is secured on the head 24 and is adapted to telescope over the upper end of the fusee body. A suitable pad 27 is placed inside the sleeve 26 to engage the ignition material 19 in the manner shown in Fig. 1.

The cap is secured in place on the fusee by means of a piece of adhesive tape 28 that is adhered directly to the side of the sleeve 26. The scratcher material 25 is small enough in area to be entirely covered by the tape 28. The tape 28 is water-proof and can be loosened and stuck back again several times before it loses its adhesive qualities. It will be noted that the tape has its portion 29 sufficiently long to extend completely over the head 24 and lap down on the opposite side of the cap. It is also long enough to have a substantial portion 30 extend beyond the cap at the open end for attachment to the body of the fusee.

In Fig. 2, the fusee is shown with the cap reversed and the scratcher material 25 exposed readily to engage the ignition material 19 and ignite the fusee. The fusee in burning produces a sort of well, as indicated at 31 in Fig. 3. The residual material left after burning runs down over the outside of the tube 22 and the upper edges of this tube and the inner tube provide a rim around the burning chemical. It is customary to so construct the paper tubes as to control the time of burning of the fusee to a certain degree. Care must be taken, however, that the tubes do not break down so slowly in burning as to produce a chimney around the burning chemical that would obscure the light. It is highly essential that throughout the burning of the chemical the tubing be substantially of the same character in order that the burning may be substantially uniform. It will be observed from an inspection of Fig. 1 that in the present case there is practically no change in the thickness of the paper tubing about the chemical from one end of the fusee to the other.

While the thickness of the tubing about the chemical remains substantially uniform throughout the length of the fusee, the strength thereof, insofar as its resistance to breakage, is weakened at the junctions of the sections 12, 13 and 14. This is accomplished by having the inner tube cut off so that it merely rests upon the next lower tube without any intervening closure. The advantage of this construction is illustrated in Figs. 5 and 6 where a partially burned top section of the fusee is broken off by striking the fusee a sharp blow at the point 33. This causes the outer tube 22 to break at the junction of the inner tubes 16 and 17. The operator, therefore, saves the two lower sections 12 and 13 of the fusee. He places the cap 23 in position on the section 13 and secures the tape 28 in place to protect the scratcher material 25 and to prevent accidental detachment of the cap.

It is believed to be evident from the foregoing 70

description that the present fusee provides all the advantages of a single fusee for a definite length of time. It provides also the advantages of a plurality of short fusees without increasing the storage space necessary for such fusees and without in any way adversely affecting the use of the device as a single fusee. It is obvious that the several sections may comprise more than the three shown in Fig. 1 where the need therefor exists. It is believed to be obvious that other methods of so weakening the connection between the adjacent sections as to enable their separation may be employed. The present invention in its broader aspects is directed toward the provision of a single fusee in a plurality of sections end to end, so arranged that the several sections may be burned as a continuous unit and alternatively as individual units with the advantage of salvaging those units not ignited.

From the foregoing description it is believed that the features and advantages of the present invention will be readily apparent to those skilled in this art. Having thus described my invention, what I claim as new and desire to secure by Letters Patent is:

1. A fusee of the character described comprising a base plug having a fusee supporting member secured thereto, a plurality of separate paper tubes arranged end to end on said base plug, each tube having a filling of combustible chemical and ignition material embedded in the combustible chemical at the end of the tube most remote from the base plug, a paper tube enclosing the several sections and secured to the base plug, and a cap member telescoped over the end of said last named tube opposite the base plug.

2. A fusee of the character described comprising a base plug having a fusee supporting member secured thereto, a plurality of separate paper tubes arranged end to end on said base plug, each tube having a filling of combustible chemical and ignition material embedded in the combustible chemical at the end of the tube most remote from the base plug, a paper tube enclosing the several sections and secured to the base plug, a cap member telescoped over the end of said last named tube opposite the base plug, said cap having scratcher material on the head thereof, and a waterproof adhesive tape covering the scratcher material and adhering the cap to said outer tube.

3. A fusee of the character described, comprising a plurality of sections of combustible material superposed end to end upon a base, a small body of ignition material mounted on the combustible material at the top of the fusee, another small body of ignition material mounted on the top of each section below the section having the first named body of ignition material thereon whereby to provide a body of ignition material upon each section in position to ignite that section after removal of the superposed section, and supporting tubing of uniform thickness for said sections, the tubing being weakened at the junction of the sections so that the sections may be readily separated into separate shorter fusees.

RAYMOND F. HUTT.
